UNITED STATES PATENT OFFICE.

WALTER GOODCHILD, OF OAKLAND, NEW JERSEY, ASSIGNOR TO "NIPS" INCORPORATED, OF HOBOKEN, NEW JERSEY, A CORPORATION OF NEW JERSEY.

APPARATUS FOR FILLING AND CLOSING CAPILLARY CONTAINERS.

Application filed June 1, 1921. Serial No. 474,236.

To all whom it may concern:

Be it known that I, WALTER GOODCHILD, a citizen of the United States, and a resident of Oakland, in the county of Bergen and State of New Jersey, have invented a new and useful Apparatus for Filling and Closing Capillary Containers, of which the following is a specification, reference being had therein to the accompanying drawings.

This invention relates to the filling and sealing of containers, primarily those of restricted capacity, for holding various liquids, such as perfumes, oils, chemicals, medicaments, etc.

The apparatus herein described is adapted particularly, though not exclusively, to packaging delicate and costly perfumes; the containers for the perfumes being capillary tubes, which are to be broken open by severing or snapping their opposite extremities when it is desired to use the contents. These tubes when filled contain a quantity of perfume usually sufficient for one application, and are hermetically sealed so that wastage from leaking or evaporation is impossible. The perfumes or other goods are therefore fresh and pure until released by unsealing the ends of the receptacles containing the same.

The primary object of the invention is to provide means of a simplified nature for expeditiously filling and sealing the receptacles or capillary tubes, whereby large quantities of them may be filled and closed in a very short time, the same permitting either or both of the operator's hands to be used, practically eliminating loss of the liquid by evaporation in the filling and sealing process, and enabling the apparatus to be so arranged, assembled and positioned that space is greatly economized, and duplicates or a number of such apparatus can be joined and comfortably located in a comparatively small apartment.

A further object of the invention is to supply a filling and sealing apparatus of such nature that little or no skill is required on the part of the operator in carrying out the process successfully, and through which with little practice the operator may easily and with less effort accomplish more and better results than has been possible with apparatus heretofore proposed and used for similar purposes.

A further object resides in producing an apparatus of the character and for the purposes mentioned which has its filling and sealing adjuncts, such as air and gas jets, severally supplied from a single source common to jets of similar type, and by means of which, if desired, two or more units composing the apparatus may jointly be operated from the same sources.

Other objects and advantages of the invention will in part be obvious and in part be more fully brought out in the following description.

The invention consists in the novel improvements, parts, combinations, and features of construction herein described and illustrated.

In the accompanying drawings is shown a practical embodiment of the invention, the same serving to explain its principles, in connection with the descriptive matter hereinafter contained.

In the said drawings, Figure 1 is a plan view of a part of the apparatus where the tubes are filled and closed at one end; Fig. 2 is a vertical section taken substantially on the line 2—2 of Fig. 1; Fig. 3 is a similar view taken along the irregular line 3—3 of Fig. 1; Fig. 4 is a top plan view showing a slight modification of the apparatus shown in Figs. 1 to 3; Fig. 5 is a sectional view taken on line 5—5 of Fig. 4; Fig. 6 is a detail section taken through a combined tube and liquid holder shown in Fig. 4; Fig. 7 is a plan view showing another part of the apparatus which is by preference employed in finally sealing the filled tubes; Fig. 8 is a vertical section taken substantially on the irregular line 8—8 of Fig. 7; and Fig. 9 is a front view of the middle portion of the structure shown in the latter-named figure.

The containers for the perfume or other liquid are conveniently made from glass tubing, drawn down to a very light caliber, the central portion of the length of each tube being preferably of greater transverse dimension than the end portions thereof to provide capillary terminals only. It will be understood, therefore, that the openings through the restricted end portions of the several tubes are exceedingly small. These tubes are designated by the reference numeral 10 in the various figures of the drawings.

The capillary tubes aforesaid are brought to the apparatus open at both ends, and quantities of them are placed transversely in trays 11, upon a shelf 12, supported from a stand 13, set on a table 14 so as to be in reach of an operator seated in front. Extending upwardly from the table, slightly in advance of the trays, is a pipe 15, with a nozzle 16, adapted to deliver a jet of air, as from a blow-pipe, the same being supplied from a compressed air tank, indicated at 17 in Fig. 3. The nozzle 16 discharges the air in a substantially vertical direction above the table. On one or both sides of this pipe 15 are receptacles 18, containing the liquid to be forced or drawn into the tubes.

In the preferred embodiment of the invention the receptacles 18 are covered as shown in Figs. 1 to 3, but their tops or lids 19 are apertured, as at 20, near the inner end of each, the apertures being small and only large enough to receive and accommodate the end of a tube to be filled. The outer edges also of the apertures 20 are notched, as at 21, the notches being substantially equal to the transverse width of the restricted or capillary ends of the tubes. The nozzle 16 of the air-pipe is formed with similar notches 22, adapted to receive the upper ends of the tubes and to steady the same while the filling takes place. It will be noted that the notches 21 and 22, respectively provided in the receptacle cover and pipe nozzle, act as a guide in the filling operation, and enable the operator to place the empty tubes quickly in position for filling. It is to be observed further that the air nozzle and liquid receptacle are such distances apart that a tube, when resting in the receptacle and limited in movement by the outer edge of the opening in the cover thereof, is given an inclination such as will bring its upper end into the zone of the air issuing from the nozzle, as clearly indicated in Fig. 2. With the lower end of the tube immersed in the liquid in the receptacle, it is obvious that the air draft at its upper end operates to reduce the atmospheric pressure in the tube to such degree that the liquid will flow up into the same. It is likewise apparent that with but a moderate air pressure at the nozzle, the liquid from the receptacle will very quickly enter the tube, and the filling operation is promptly performed. It is only required, therefore, to keep a tube in its inclined position for an instant; and by reason of the arrangement of receptacles 18 on both sides of the air-pipe 15, the operator may use both hands in carrying out the filling of the tubes.

Immediately in advance of the pipe 15 is a burner 25, providing a flame jet 26, and supplied with gaseous fuel by suitable conduits, as 27, projecting upwardly from under the stand 13. The flame from this burner

is directed away from the operator, between upright plates constituting laterally disposed guards 28, and is preferably projected in a horizontal plane parallel with the upper edges of the said plates. The said upper edges of the plates are provided, for convenience, with aligned notches or recesses, indicated at 29, to receive the restricted end portions of the tubes. After a tube has been filled, one end thereof is placed transversely of the notch in either plate, in the path of the flame jet 26, and held there sufficiently long for the glass to fuse and thus seal the tube end. By reason of the thinness of the glass at this point, fusion takes place immediately.

The filled tubes, each with one end sealed, are deposited in open-ended receivers 31, lengthwise thereof, as shown by dotted lines in Figs. 1 and 4 of the drawings. A large number of such tubes, sealed only at one end, may be collected in these receivers, before they need be closed at the other end.

Figs. 4 to 6 of the drawings disclose a slight modification of the filling and initial sealing part of the apparatus, wherein a pair of air nozzles 34, 35, connected with the pipe 15 by a Y-fitting 36 and intermediate branch pipes 37, are employed, one for each hand of the operator. In this instance, the empty tubes and the liquid are placed in holders 40, 41, common to both. By preference, these holders are convergently arranged, with their forward ends turned inwardly at an angle from the front edge of the shelf 12, through which the nozzles 34, 35 project. The forward ends of the holders may be indented, as at 42, 43, to take around and partly embrace the adjoining nozzles. The empty tubes are intended to occupy approximately two-thirds of each holder, at the rear thereof, in the forms shown in Figs. 4, 5 and 6. The remaining forward portions of the holders are shaped so as to provide wells 44, 45, into which is poured the liquid wherewith the tubes are to be filled. These wells are partly covered by plates 46, 47, which leave openings or slots 48, 49 along their outer sides, permitting insertion of the lower ends of the tubes that are to be immersed in the liquid. The slots or openings, it will be observed, are situated on the sides of the holders remote from the upstanding nozzles 34, 35. The sides of the holders that are nearest to the nozzles are curved up toward the latter, as at 50, Fig. 5. The nozzles themselves are curved to correspond, as at 52, and formed also with an abutment 53, against which the upper end of a tube may be brought to bear for the filling operation. It will be perceived that the operator can rest this end of the tube upon the curved side of the holder to slide it into filling position, and by holding the tube downwardly inclined, its lower end will naturally be car-

ried forward and led into the opening, 48 or 49, of the well that contains the perfume or other filling substance.

Curved guards 56, 57, set on edge upon 5 the shelf 12, are placed forwardly of the pair of nozzles 34, 35 above described, the same being used, in the form of the apparatus represented by Figs. 4 to 6, as substitutes for the straight guards 28, before mentioned and illustrated in Figs. 1 to 3. Like 10 the latter, the guards 56, 57 are positioned on opposite sides of the flame jet 26 of the burner 25, transversely of the shelf, in the middle forward portion thereof. The front 15 halves of the guards last named are preferably made straight and parallel one to the other, as shown, but their rear halves are deflected outward so as to reach the upper ends of the paired nozzles. The tubes that 20 have been filled with perfume can therefore be slid directly from the nozzles to and along the upper edges of these guards, in such a manner that one of their capillary ends will be brought into the flame and 25 sealed immediately after the filling has been effected. Depressions, as 59, are provided in the said upper edges of the curved guards, to receive and temporarily retain the tube ends that are being sealed. These depre- 30 sions correspond to the notches 29 in the straight guards 28, and perform the same office. Both the curved and the straight guards, it will be noted, indicate where the open-ended receivers 31 may be conveniently 35 as well as readily located, to facilitate and expedite the depositing therein of the filled tubes subsequently to sealing the same at one of their capillary extremities.

In Figures 7, 8 and 9, there is shown an- 40 other part of the apparatus, where the final sealing of the filled tubes may be effected conveniently as well as rapidly. This other part of the apparatus could be dispensed with, and the necessary elements thereof in- 45 corporated in the first part hereinbefore described whereby the filling and initial sealing are carried out, but in practice it is deemed preferable to keep these parts sepa- 50 rate, though closely associated.

As illustrated in the latter-named views, 55 the table 14 carries a second stand 62, with another pair of guards 63, 64, set edgewise in spaced relation thereon, between which is projected, as at 65, a jet of flame emitted by a burner 66. The latter is supplied with gaseous fuel, from the source previously referred to, by means of pipes, as 67, 68, passing under the stand and extending upwardly thereabove near the front of the table. A 60 small plate 69 is laid across the upper ends of the pair of guards, in position to be heated by the flame, directed under it, as suggested in Fig. 7. The hot plate 69, thus lying in the path of the flame from the 65 burner 66, is used for preheating the end

of the filled tube which is the second or last to be sealed. The preheating causes expansion of the liquid in the restricted open portion of the tube and relieves it of any surplus filling that might interfere with the final sealing operation.

Subsequently to being preheated, each tube is advanced toward the operator, so that the capillary end thereof, still open, may be rested in either one of a pair of 70 aligned notches 70, 71, provided at the upper edges of the guards 63, 64. There, the outer extremity of the preheated part of the tube is exposed directly to the flame, while the adjoining restricted tube portion is subjected to a cooling medium, such for instance as a current or blast of cold air, issuing from pipes 72, 73, and preferably supplied through a series of branch-pipes as 74, connected with the air-tank 17, shown in Fig. 3 80 and previously referred to herein. It will be noted that the pipes 72, 73 are directed upwardly and obliquely toward the notched portions of the guards 63, 64. Each one of the notches 70, 71, it will further be seen, 85 constitutes a stop or guide for the open end of the tube remaining to be sealed, and assists in properly positioning the same for final sealing.

The combined action of the flame from the burner 66 and of the cold air blast supplied by either one of the pipes 72, 73, effects the final sealing. As will be understood, the flame is directed against the extremity of the tube, to close it by fusing the glass at that point, and in the meanwhile the air jet cools off the preheated portion adjacent to the tubular body. The cooling of this intermediate portion causes contraction of the contents at or near the tube end, 90 which was previously freed from its excess of filling substance through the preheating. The tube being relieved of internal pressure, the melting glass at the extremity last to be sealed is driven inwardly, owing to the external atmospheric pressure, and forms a practically solid stem, tightly closing the tube end and rendering it proof against leakage.

After the preheating and final sealing operation, the filled tubes may be placed in some of the open-ended receivers 31, hereinbefore mentioned with reference to the filling and initial sealing. As indicated in Figs. 7 and 8, these receivers are located 100 upon the stand 62, exteriorly of the pair of cooling air-pipes 72, 73.

Having thus described my invention, what I claim, and desire to secure by Letters Patent of the United States, is:—

1. An apparatus for filling capillary tubes with liquid, including a blow pipe, a receptacle for the liquid adjacent thereto, and means serving to hold a tube so that one end thereof will be immersed in the liquid

- while its other end lies in the path of discharge from said pipe.
2. An apparatus for filling capillary tubes with liquid, including a blow pipe, and a receptacle for the liquid having a tube retaining means forming a part thereof, said means coacting with said receptacle in holding the lower end of the tube immersed therein at a point remote from said pipe and its upper end reclining against the latter in the path of its discharge.
3. An apparatus for filling capillary tubes with liquid, including an air-pipe, a receptacle for the liquid disposed below the same, and a stop pertaining to said receptacle adapted to hold a tube inclined upwardly therefrom toward said pipe in such manner that the lower end of the tube may be immersed in the liquid while the upper end thereof is exposed to a current of air.
4. An apparatus for filling capillary tubes with liquid, including an air pipe, a guide associated therewith, a receptacle for the liquid adjacent to said pipe and its guide, and a stop serving to maintain the lower end of a tube immersed in said receptacle while the upper end thereof is received in said guide in position to be acted upon by the air issuing from the pipe.
5. An apparatus for filling capillary tubes with liquid, including a blow pipe, a receptacle for the liquid, and an apertured cover for said receptacle capable of holding one end of a tube immersed in the liquid therein while the other tube end is exposed to the action of said pipe.
6. An apparatus for filling capillary tubes with liquid, including a blow pipe, a receptacle for the liquid situated below said pipe adjacent to the same, and a cover for said receptacle formed with an opening, one edge whereof constitutes an abutment for the lower end of a tube to be filled, while the opposite extremity of the latter is acted upon by the discharge from said pipe.
7. An apparatus for filling capillary tubes with liquid, including a blow pipe, oppositely disposed guides associated therewith receiving the upper ends of the tubes so as to expose them to the discharge from said pipe, means for supplying the liquid to the tubes adapted to receive the lower ends thereof, and stops serving to position the latter with relation to said means and said guides.
8. An apparatus for filling capillary tubes with liquid, including a blow pipe, liquid holding means disposed below the latter on either side thereof, and guides adapted to maintain the tubes with their opposite ends positioned in operative relation to said pipe and said holding means.
9. An apparatus for filling capillary tubes, including a receptacle for the filling substance, means for holding in proximity thereto one end of a tube to be filled, and other means operating to apply air under pressure exteriorly outwards to the other end of said tube.
10. Apparatus for filling capillary tubes, a receptacle for the filling substance, means for reducing the pressure in the tubes, and means for holding the ends of each of said tubes in a definite predetermined position with respect to the receptacle and the pressure reducing means during the filling operation.

WALTER GOODCHILD. [L. S.]
